UNITED STATES PATENT OFFICE.

HERMANN DURLACHER, OF HAMBURG, GERMANY, ASSIGNOR TO THE FIRM: VEREINIGTE CELLULOIDWARENFABRIKEN GESELLSCHAFT MIT BESCHRÄNKTER HAFTUNG, OF KREFELD, GERMANY.

HAIRDRESSING IMPLEMENT.

Application filed December 20, 1926, Serial No. 156,022, and in Germany October 13, 1926.

The present invention refers to a hair dressing implement which is particularly well adapted to treat or dress bobbed hair. The ladies' bob-frisures now-a-days require, as experience proves, to be well taken care of. Females having had their hair bobbed therefore generally have combs with them for occasional use. The usual brushes mostly are too unhandy to be carried about. Now brushes, it is true, exist which may be placed in hand bags, however, they are always independent implements for themselves.

The present article which no doubt may be also useful for men, combines in itself a comb and a brush in such manner that the comb teeth and the bristles project in opposite directions. Another feature of the invention consists in a peculiar construction of the comb proper, which differs from the usual combs in this that the teeth are made short and emerge from furrows, which may be said to be created by partly filling up the gap between the teeth. This construction has the advantage that the hair is not injured too much, when making use of the implement. A too frequent use of a comb having the usual long teeth as experience shows not only is detrimental for undulations or curls but even for the hair itself, since by combing frequently a loss of hair is noticed. The particular shape of the new comb has the effect, it is true, of a less thorough combing, but more of a smoothing. This fact together with the bristles on the back of the comb turns it into a very practical and simple hair dressing implement, which conveniently may be carried about in a pocket and answers all purposes of a lady. In the drawing an implement is shown by way of example, which answers the requirements of the present invention.

Fig. 1 is an elevation, and

Fig. 2 an end view of the implement.

45 Figs. 3 and 4 are end views of modifications.

In the construction shown the comb-body 5 is provided with a handle 4 and with short comb-like teeth 6. These teeth differ from those of an ordinary comb inasmuch as the intermediate spaces or gaps are halfway or approximately halfway filled up in such manner that those parts of the gaps which are near the central plane of the implement constitute furrows 7 which by degrees run out into nothing. The brush 8 which is applied to the back of the body 5 of the comb may comprise any desired number of rows of bristles, one, two and three rows being shown in Figs. 3, 4 and 2 respectively. The brush may be integral with the body of the comb as shown in Fig. 2, or may be detachable for facilitating cleaning. With this object in view the bristles are attached to a bar 10, which in the construction shown in Fig. 3 is of U-shaped cross-section, and in the construction shown in Fig. 4 is dove-tailed. In the former instance the bar 10 embraces a correspondingly shaped offset or shoulder 9 of the body 5, and in the latter case it fits into a dove-tailed undercut groove in said body.

The material of which the implement is made may be horn, bone, ivory, celluloid, galalite, artificial horn or the like.

I claim:

A hair dressing implement comprising a combination comb and brush forming a unitary structure, the brush having its bristles projecting in a direction opposite to but in the same central plane as the teeth of the comb and being slidably detachable from the body of the comb, and the comb having gaps between the teeth merging into furrows in the body of the comb and forming web-like portions between the teeth whereby the teeth proper are correspondingly shortened.

In testimony whereof I have signed my name to this specification.

HERMANN DURLACHER.
